OF BERNE, SWITZERLAND, A SWISS CORPORATION.

TIME-RECORDING ATTACHMENT FOR SPEEDOMETERS.

1,356,116.

Specification of Letters Patent. Patented Oct. 19, 1920.

Application filed October 11, 1919. Serial No. 330,147.

To all whom it may concern:

Be it known that we, OTTO ABEREGG and ULRICH KOHLER, both citizens of the Swiss Confederation, and residing at Berne, Switzerland, have invented certain new and useful Improvements in Time-Recording Attachments for Speedometers, of which the following is a specification.

The present invention has for its object 10 a device designed for use in connection with a speedometer for diagrammatically recording the time of day on a recording surface, such as a paper record sheet or ribbon which is fed in correspondence with 15 the travel speed of the vehicle on which the speedometer is mounted. A well known defect of such registering devices in which the time of day is recorded by a single stylus is the difficulty of quickly and cor- 20 rectly reading off the diagrams owing to the relatively restricted width of the recording surface, which is apt to lead to mistakes if the checker is not very careful and expert. For doing away with this draw- 25 back there are provided in the device forming the subject of the present invention two such time recording members, both controlled from a common clock work, the one with quick feed for recording the minutes, 30 and the other for recording the hours on correspondingly slower feed.

Our invention will best be understood when described in detail in connection with the accompanying drawing, in which Fig- 35 ure 1 is a side elevation; Fig. 2 a vertical section, and Fig. 3 a plan view partly in section of a preferred form of construction of our improved time recording attachment for speedometers; Fig. 4 is a view of the 40 record sheet showing the record covering a ten hour run, the marginal references indicating the length of time the car was idle and at what time.

Through the vertical support plate 1 ex- 45 tends horizontally the hour shaft 2 of a clock work, not shown here, for driving the speedometer mechanism. On the right hand portion of this hour shaft 2 (as viewed in Fig. 2) and close to the plate 1 is fixed a 50 disk 4 provided with a driving tooth 3. On the circumference of this disk 4 can slide the hook nose 5 of a spring influenced pawl 6, which latter is fulcrumed at 26 to a disk 7 which rides idly on the hour shaft, the

outer extremity 36 of said pawl 6 extending 55 somewhat beyond the periphery of the disk 7. On rotation of this driving disk 4 in clockwise direction the disk 7 will correspondingly be taken along once the hook nose has caught behind the tooth 3. A 60 toothed wheel 8 fixed to the disk 7 meshes with a rack 9 and on rotation shifts the rack 9 in vertically upward direction. The 65 diameter of the wheel 8 is such that for a complete revolution thereof the rack 9 is 70 displaced to an extent which corresponds exactly to the diagram width of a paper sheet or ribbon 11 which is fed in suitable manner above the support plate 1 longitudinally in front of a plate 10 at a velocity 75 corresponding to the speed of travel of the vehicle.

The simultaneous recording of the minute and velocity diagrams is caused by means of the writing stylus 12 fixed to the upper 75 end of the rack 9, and this only during the upward movement of the latter, and it recommences after each completed hour. The rack is released or tripped in its upper 80 end position by a pin 13 fixed in the plate 1, against which the pawl end 36 strikes, which then causes the hook nose 5 to be lifted free of the tooth 3 of disk 4, so that then the coupling connection between the 85 two disks 4 and 7 is broken. The rack 9 now by its own weight and also by the downward pull exerted on it by a draw 90 spring 14 drops vertically down, causing thereby the toothed wheel 8 with the disk 7 to rotate backwardly a complete revolution, that is to say until the free end 36 of the pawl 6 again contacts with the pin 13, but at the opposite side thereof. Immediately thereafter the above described operation commences again, the disk 7 being 95 taken along by the disk 4 owing to the pawl nose 5 again coöperating with the driving tooth 3.

The recording of the hour diagram is ef- 100 fected in similar manner, with the exception that the record is not traced out but is pricked into the record sheet from the oppo- 105 site face thereof. On the left hand por- tion of the hour shaft 2 ride loosely the disks 4' and 7', in construction and operation simi- 110 lar to the above described disks 4 and 7. To the disk 4' is fixed a toothed wheel 15 and to the disk 7' a toothed wheel 8'. The wheel

15 and thus also the disk 4' are revolved once in 24 hours by the clock work, and by the intermediary of the pawl 6', fulcrumed to the disk 7', this latter disk with its 5 toothed wheel 8' will be correspondingly rotated. Secured to the shaft 2 is a gear wheel 50 meshing with a larger gear wheel 51 fixed to a shaft 52 extending parallel to shaft 2. Also fixed on shaft 52 is a pinion 10 53 in mesh with the toothed wheel 15. It will be noted that shaft 52 is driven from shaft 2, but the ratio of gears 50 and 51 is such that the pinion 53 will rotate the wheel 15 once for each twenty four revolutions of 15 the disk 4 effected by the shaft 2. The rack 9' meshing with the wheel 8' is guided at its upper end, which is provided with a pin or pricker 16 (Fig. 3), in a vertical slot 17 of a plate 19, which latter can be oscillated 20 about the vertical axis 18. This plate 19 is positioned behind the plate 10 in the rear of the record sheet 11 and is normally kept in such a position by a leaf spring 29 that the pricker 16 is out of contact with the record 25 sheet. This slotted plate 19 is controlled in its oscillation about the axis 18 by a rock member 21 which is fulcrumed at 22 to the upper extremity of the support plate 1, extending crosswise thereto and presenting an 30 upwardly directed finger 20 designed for co-operation with the lower edge of the plate 19, and a tooth 23 adapted to co-operate with a projection 24 extending from the rack 9 near its upper end. This projection 24 35 strikes the rock member tooth 23 from above on the rack 9 dropping suddenly from its upper end position into its lower one, with the result that the member 21 is so rocked about its fulcrum that its finger 20 forces 40 the plate 19 with the rack 9' toward the plate 10 and the record sheet 11, causing the pricker 16 to pierce the latter. These pin pricks will be repeated every hour at a higher point, and in connection with the line 45 traced by the stylus 12 will clearly show the exact time of registration at any point of the diagram. Every time the rack 9' has reached its highest position, that is to say every 24 hours, it will be tripped by the 50 pawl 6' contacting with the pin 13' and being thereby lifted free of the disk 4'. The down-movement of the rack 9' is caused partly by its own weight and partly by a draw spring 34. 55 As shown in Fig. 3 the stylus 12 is somewhat displaced laterally relative to the pricker 16 so that it does not operate on the record sheet at the point where the latter passes in front of the slot 17 in the plate 10 60 through which the pricker 16 operates. Obviously, instead of being pricked-in, the hour registration could also be recorded by a traced-out line, if for instance the record sheet is advanced past the rack 9' in its rear, 65 in which case the pricker 16 would have to

be replaced by a writing stylus positioned on the opposite face of the rack, and the stylus 12 would then have to be extended to make contact with the record sheet. It would appear, however, that the difference in the registration by the two recording elements, the writing member and the pricking member, has the advantage over two writing members that the line representing the speed diagram proper is not crossed by a second line, 70 representing mainly the hour diagram, which would tend to confuse the picture of the diagram. 75

What we claim is:—

1. The hereinbefore described speedometer attachment for recording the time of day on a record surface advanced in correspondence with the travel speed of a vehicle, which comprises the combination of a recording member for minute registration with quick 80 operative feed and actuation, a recording member for hour registration with correspondingly slower operative feed and actuation, and a common clock work for actuating both of said recording members. 90

2. In the hereinbefore described speedometer attachment for recording the time of day on a record surface advanced in correspondence with the travel speed of a vehicle, in combination with a common clock work, 95 two racks actuated thereby, recording elements on said racks, toothed wheels journaled on the hour shaft of said clock work and driven at different velocities and respectively meshing with said racks, and means 100 for tripping said racks in their operative upper end position for allowing them to drop back into their initial lower end position.

3. In the hereinbefore described speedometer attachment, in combination with a 105 clock work including an hour shaft, two units for recording the minutes and the hours respectively and each comprising a one-tooth driving wheel driven from the hour shaft of said clock work, an idle disk, 110 a toothed wheel fast thereto, a pawl coupling between said one-tooth driving wheel and said idle disk, and means for automatically uncoupling said parts at the completion of each revolution thereof, a rack 115 meshing with said toothed wheel, a recording element on said rack, and means for aiding said rack in its down-movement on release of said pawl coupling, one of said units for recording the minutes completing 120 the operative cycle once every hour and the other one for recording the hours once every 24 hours.

4. In the hereinbefore described speedometer attachment, in combination with a 125 clock work including an hour shaft, two racks, recording elements on said racks, toothed wheels journaled on said hour shaft and driven by the latter at different velocities and respectively meshing with said 130

racks, means for tripping said racks in their uppermost operative position, and means for so interdependently connecting the said racks that the one is momentarily forced toward the record surface of the speedometer upon the other one returning to its lowermost initial position.

5. In the hereinbefore described speedometer attachment, in combination, two operatively associated racks, recording elements on said racks, one of said recording elements being in the form of a writing stylus and the other in the form of a pricker, and means for feeding and recordingly actuating said racks at different velocities.

6. In the hereinbefore described speedometer attachment, in combination, two operatively associated racks, recording elements on said racks, means for actuating said racks at different velocities, and said two recording elements respectively operating on the recording surface of the speedometer from opposite sides.

7. In the hereinbefore described speedometer attachment, in combination with a clock work and a record surface operated thereby, two racks, a slotted member guiding the upper end of one of said racks, recording elements on said racks and the latter to be operated by said clock work at different speeds, a projection on the faster operated rack, a rock member presenting a finger and a tooth, the latter adapted to co-

operate with said rack projection and said finger adapted to coöperate with said slotted guide member for recordingly actuating the respective end of the guided rack on said rock member being oscillated by said rack projection on the other rack coöoperating with said rock member tooth.

8. In a speedometer attachment for recording the time of day on a moving record, recording elements at opposite sides of said record, means for traversing both of said elements across the faces of said record, and means for rocking one of said elements to perforate said record.

9. In a speedometer attachment for recording the time of day on a horizontally moving record, recording elements at opposite sides of said record, means for feeding both of said elements vertically across the faces of said record, and means for rocking one of said elements toward and away from said record.

10. In a speedometer attachment for recording the time of day on a moving record, recording elements at opposite sides of said record, common means for advancing said elements at different speeds across the faces of said record, and means for periodically rocking one of said elements toward and away from said record.
